UNITED STATES PATENT OFFICE.

WILLIAM ARMSTRONG FRIES, OF BROOKLYN, NEW YORK.

ASBESTUS STEAM-PACKING.

SPECIFICATION forming part of Letters Patent No. 295,749, dated March 25, 1884.

Application filed January 31, 1883. (Model.)

To all whom it may concern:

Be it known that I, WM. ARMSTRONG FRIES, a citizen of the United States, residing at Brooklyn, in the county of Kings and State of New York, have invented certain new and useful Improvements in Gland-Packings; and I do hereby declare the following to be a sufficiently full, clear, and exact description thereof to enable others skilled in the art to make and use the said invention.

This invention relates to that class of steam-gland packings made from asbestos strands or yarns.

Heretofore steam-packings made from asbestos strands or yarns have been made by the side-drawing operation of a card, which can only make a thick heavy strand, and by which process the asbestos splints remaining in the asbestos stock after carding, together with sand or grit, are twisted in and carried along with the asbestos fiber into the strands or yarns, which splints and grit are objectionable in packings, and, by cutting, very injurious to piston-rods, and the strands being thick and heavy, it is impracticable to twist them hard, and, being soft, have but very little strength, makes them difficult to make into packings, and when packing made from such yarns is placed in a stuffing-box it becomes inelastic and soggy.

The object of my invention is to provide a packing composed entirely or in the main of fine hard spun or twisted yarns, which yarns may be of pure asbestos or other mineral fibers; or said yarn may contain a central organic core or thread; or said yarn may be composed of asbestos or other mineral fibres, combined in mixture with other organic fibers—such as cotton, wool, linen, jute, hemp, silk, and like material—but should be mainly of asbestos; but, for convenience of description, I shall call the stock as described above as simply "asbestos stock," and the yarn made therefrom "asbestos yarn."

Figure 1 of the drawings shows a piece of packing in perspective; Fig. 2, a cross-section, and Fig. 3 a longitudinal section.

To carry my invention into effect, I card the asbestos stock by the usual mode. It is then placed on a woolen finishing-card, which forms it into slubbing, which is then placed in a self-operating or hand mule; or it may be

spun on a spinning-jack or like machine and spun into yarn. During the process of spinning, and while the carriage of the mule or jack is being drawn out, the strands begin to twirl, and do so for considerable time after the carriage is out, until sufficient twist is put in the yarn. The slubbing made on the finishing-card, not having any twist put in it before being placed in a mule or jack, and being much finer, will stand a great deal more twirl. This twirl has the effect of throwing off the asbestos splints, sand, and gritty matter, objectionable in packings, remaining after the carding process, by the centrifugal force developed by the twirl in spinning.

Yarn made by this process is more uniform in thickness and in strength, and can be made much finer than by the side-drawing process; hence it may be harder twisted, which prevents the packing made from it from becoming loose, inelastic, and impacted. Being fine hard spun or twisted strands, when placed in a stuffing-box and pressure is brought against it by screwing up the gland, the strands roll on each other and press out laterally against the rod, making it an effectively elastic packing.

Yarn made by this process is stronger, therefore involves less waste and loss of time from breaking strands than is incurred in the manufacture of packings from yarns made by a side-drawing process. It can be woven into cloth for gasket-packing, woven or braided into tape or ribbon for gasket-packing, or formed into rope packing or for braiding packings, or for making solid braided packings, or for hollow braided packings, or any other kind or variety of packing other than wick packing.

I am aware that rod-packings have been made, as appears in English Letters Patent No. 3,392 of 1881, to Allport and Hollings, wherein parallel or slightly-twisted strands of asbestos were covered by thick strands of warp-threads longitudinally woven thereon, with a circumferential weft-thread. Such packings are objectionable, because large strands of asbestos are incapable of being hard twisted or spun by reason of their large diameter, and by absorption of water become soggy and impacted by the pressure of the gland, and fail to press laterally against the rod, while hard-spun yarns of asbestos roll on each other, and

are thus forced against the rod when the gland is screwed down; and, further, such packings of large strands include splints or harsh particles of asbestos and gritty foreign matter, 5 which are thrown off and rejected by the centrifugal force generated by the twirling motion in spinning fine yarns of asbestos. Neither is it practicable to interlock the fibers of heavy yarns by twisting, as in fine hard-spun yarns, 10 and as a consequence the loose fibers of the packing formed of heavy yarns blow out of the stuffing-box through the gland. Said packings of heavy yarns I hereby disclaim; but

What I claim is—

As an improved article of manufacture, a 15 steam-rod packing made entirely from fine hard-spun asbestos yarns inclosed in a braided covering of similar yarns, as set forth and described.

WM. ARMSTRONG FRIES.
